Inventor;
T. G. Beecher

UNITED STATES PATENT OFFICE.

T. G. BEECHER, OF BEAVER DAM, NEW YORK.

FARM-FENCE.

Specification of Letters Patent No. 25,944, dated November 1, 1859.

To all whom it may concern:

Be it known that I, T. G. BEECHER, of Beaver Dam, in the county of Schuyler and State of New York, have invented a new 5 and Improved Mode of Constructing Farm-Fences; and I do hereby declare that the following is a full and exact description of the same, reference being had to the accompanying drawings, making part of this 10 specification, and to the letters of reference marked thereon, in which—

Figure 1 is a view in elevation. Fig. 2 is a view of one of the piers, the rails and earth being represented in section. Figs. 3 15 and 4 represent the method of inserting and locking the rails within the posts or piers, so that they may be conveniently removed to form a passage way, and for other purposes as hereinafter explained.

20 Similar letters refer to corresponding parts in all the figures.

My fence, which I denominate the Yankee composite fence, is designed for permanency, and is adapted to those farming districts 25 where stones exist upon the ground in such abundance as to render their removal desirable. In such localities, and they are numerous throughout our country, the principal material used is supplied at the mere 30 cost of the labor which is necessarily incurred in removing them from the soil, while the reduced amount of timber required for rails, and the durability of the fence renders it cheap beyond comparison.

35 As shown in the drawings A A, represent the piers or posts, B the rails, and C the earth.

My method of construction is as follows: Having provided upon the ground a suitable 40 number of rails, which may consist of common split rails, round poles, or saplings, or, for a better quality of fence, of sawed scantling, I mark the localities for the posts along the line where the fence is to be 45 erected, according to the length of the rails, which should be of the ordinary length used for other kinds of fence. The stones as they are gathered from the field are drawn to the spot and as they are unloaded are laid up 50 in rough mason work without mortar, beginning at the surface of the ground with a pier which may be at the base from two to three feet, or thereabout, in diameter, and diminishing to about two or less at the top.

55 If the material is abundant the piers may be

larger, but if not a smaller size will answer. The laying requires but slight mechanical skill, as the stones are used without dressing and the only care necessary is to "break the joints" of the outer corners. At the height 60 of about eighteen inches the lower rail is laid in and the stone wall is built around its ends. The others are added at suitable distances apart. The piers should be finished by placing a large flat stone at the 65 top to prevent the water from having ready ingress, but if the stones are not present of sufficient size for this purpose two or three of the largest may be used together and so arranged as to afford good protection. Previous to the fence being laid up, the ground 70 is prepared by plowing a ditch, D D, upon either side and with a scraper throwing the dirt in a bank, E, in the center directly under the rails. This has the three fold effect 75 of protecting the foundation of the posts from the injurious effects of frost, of saving the expense of one rail, so that a four rail fence is of equal height with a five railled 80 one of ordinary construction, and of making it a better safeguard against breaching cattle, as the ditch makes it difficult for them either to jump the fence or break it down, while the firm anchorage of the piers makes it stronger than any fence built of rails alone. 85

For the purpose of renewing the rails, (which will not last nearly so long as the stone piers or posts,) by removing them and replacing with new rails and the convenience of making "bars" for opening a passage way for teams through the fence the rails are notched at their ends in such a manner that by lapping the projection e of one lies in the notch f of the other. By scoring away a portion of each, on the side, 95 as shown at g, g, the turning of one will release it so that it can readily be drawn out and removed, and as easily replaced, and when in its proper position is safely secured again. The scoring and notching may be 100 done by the most unskilful person with no other tool than an ax or saw. Indeed no part of the construction of this fence requires mechanical skill, and thus it is of beneficial application to all farmers, and especially those of limited means or removed 105 from the conveniences of advanced civilization.

This method secures many important advantages, among which the very small 110

amount of lumber used, the simple labor required, the durability and permanency, with the small cost where the materials abound, may be mentioned.

- 5 I am aware that the construction of piers of stone as a part of fences is not new, and therefore this I do not claim, but I am not aware that fences have ever been constructed in a method combining and uniting the
10 various materials and devices described in a manner to form at once a cheap, durable and effective fence for farm use.

Therefore I claim as my invention and desire to secure by Letters Patent,

My improved method of construction, as 15 shown, namely, combining with the posts A, arranged as described, the rails B, made removable and replaceable by means of the locking device e, f, g, substantially as herein specified.

T. G. BEECHER.
